UNITED STATES PATENT OFFICE.

WILLIAM R. AMBROSE, OF SHEFFIELD, ALABAMA.

KNOCKDOWN AND COLLAPSIBLE CRATE.

SPECIFICATION forming part of Letters Patent No. 637,061, dated November 14, 1899.

Application filed May 13, 1899. Serial No. 716,740. (No model.)

To all whom it may concern:

Be it known that I, WILLIAM R. AMBROSE, a citizen of the United States, residing at Sheffield, in the county of Colbert and State of Alabama, have invented new and useful Improvements in Knockdown and Collapsible Crates, of which the following is a specification.

This invention relates to knockdown or collapsible crates for shipping produce, poultry, eggs, and the like, and has for its object to combine with a crate made of telescopic sections improved means for locking the sections in both their extended and folded or collapsed positions.

It has for its further object to improve and simplify the construction and render more convenient the operation of this class of crates generally.

To these ends my invention consists in the features and in the construction, combination, and arrangement of parts hereinafter described, and particularly pointed out in the claims following the description, reference being had to the accompanying drawings, forming a part of this specification, wherein—

Figure 1 is a perspective view of my improved crate, showing the sections in their extended position. Fig. 2 is a vertical sectional view taken through one corner of the crate. Fig. 3 is a detail sectional view illustrating one of the hinges of the cover. Fig. 4 is a similar view of one of the turn-buttons. Figs. 5 and 6 are detail views of a slightly-modified form of spring-catch, and also showing modified means for retracting the catches.

Referring to the drawings, the numerals 1 and 2 indicate, respectively, the two sections of a crate made in accordance with my invention, the numeral 1 indicating the lower or outer section and 2 the upper or inner section. Each of the sections comprises a four-sided rectangular frame consisting of four upright corner posts or standards 3, connected together at their tops and bottoms by rails or bars 4, and to the inner edges of the rails and posts are attached panels 5, of wire-netting or other reticulated or foraminous material, or the open spaces in the sides of the sections 50 may be slotted or wired in a well-known and usual manner. To one of the lower side rails 4 of the lower section 1 is hinged a bottom 6,

and in the opposite side rail are arranged turn-buttons 7, adapted to project through slots 8 formed in the bottom 6 and hold the latter closed. The turn-buttons 7 consist each of a rod or wire bent to form an oblong loop 9, from the center of which projects a stem 10, the end of the latter being bent at a right angle, as at 11. Holes are bored through the rail, 60 and the stems of the turn-buttons are inserted therein, after which the ends 11 are bent, as shown, over the upper edge of the rails. Metallic plates or clips 12 are nailed to the edge of the rail over the bent ends 11 of the turn-buttons to prevent any endwise movement of the latter, and said clips also serve to create a frictional resistance on the ends of the turn-buttons, and thus aid in preventing the accidental turning of the latter. When the 70 bottom 6 is closed against the under side of the lower section 1, the turn-buttons project through the slots 8 in the bottom and the loops 9 are turned at right angles to the slots, thereby holding the bottom securely against 75 the under side of the section 1.

Hinged to the upper section 2 is a cover 13. The edges of the cover 13 project beyond the sides of the section 2, so that when the latter is lowered into or nested in the section 1 the 80 cover 13 rests on the upper rails of the lower section. The cover 13 is preferably hinged to the upper section in the following manner: Formed in the outer edges of the upper ends of each of the rear posts or standards 3 of the 85 upper section is a vertical groove or kerf 14, and on a nail 15, driven into said post transversely to the bottom of the groove, is pivoted one end of a link 16, the other end of which is pivotally connected to a staple 17, driven 90 into the under side of the cover. When the cover is closed, the links 16 lie in the grooves 14 and permit the cover to close flat against the top of the upper section; but when the cover is opened or lifted the links swing automatically and downwardly, permitting the cover to drop down into the position shown in dotted lines, thus giving free access to the open top of the section on all sides for convenience in packing. This or some equivalent means for hinging the cover is employed for the reason that, owing to the edges of the cover projecting beyond the sides of the section in the manner described, ordinary leaf-

hinges, if employed, would not permit the cover to be raised or swung up beyond a vertical position. Arranged in the front upper rail 4 of the upper section are turn-buttons 18, 5 similar in all respects to the turn-buttons 7 before described, and said turn-buttons are adapted to project through slots 19, formed in the front edge of the cover, when the latter is closed, and when turned at right angles to said slots operate to hold the cover securely fastened.

Pivoted in the rear upper rail of the lower section is a turn-button 20, similar to the turn-buttons before referred to, and when the 15 upper section is lowered into the lower section the turn-button 20 projects through a slot 21, formed in the rear projecting edge of the cover 13, and when turned at a right angle to said slot operates to lock the two sections 20 together in their nested or telescoped position. It will of course be evident that the location and number of the turn-buttons and the corresponding slots may be varied or altered without affecting the results accomplished.

25 In order to lock the sections in their extended positions, I provide the following means: The upper inner portion of each of the posts or standards 3 is mortised, as at 22, and in each of said mortises is arranged a 30 spring-catch constructed as follows: The numeral 23 indicates a flat metallic spring, which is creased or bent at one end to form a loop or eye 24 and at its other end is bent to form a U-shaped hook 25. The catch is disposed in 35 the mortise with its hooked end uppermost, and a nail or pin 26 is driven through the post transversely to the slot and passes through the loop or eye 24, forming a pivot, about which the catch has an oscillating or rocking movement. 40 A coiled spring 27 is disposed between the catch and the post and operates to throw the upper hooked end of the catch inward, and this movement is limited by extending the end 28 of the catch down past the eye or loop 24, 45 so that said end will abut the post at the bottom of the mortise and prevent the spring from throwing the catch inward beyond a certain distance. This is for the purpose of preventing the spring from being displaced when 50 the sections 1 and 2 are separated. It is manifest that the catch itself may consist of a flat spring formed of steel or other suitable material and rigidly attached at its lower end to the post, thus dispensing with the coiled 55 spring, as will more fully hereinafter appear. Journaled in bearings on the under sides of the upper end rails of the lower section are rock-shafts 29, each of which is bent downward at right angles at its opposite ends to 60 form cranks 30, and said cranks are adapted to oscillate in slots 31, formed in the posts and extending through the latter into the mortises 22. To the ends of the cranks are attached wires or similar connections 32, 65 which pass through the slots 31, and at their inner ends are attached to the hooked ends of the spring-catches. Intermediate their ends

the rock-shafts 29 are formed or provided with handles 33, by means of which the rock-shafts may be turned or rocked in their bearings. 70 It will be evident that by turning the handle of either of the rock-shafts in the proper direction the cranks 30 at its opposite ends will be thrown outward and pull the hooked ends of the catches attached thereto into their 75 mortises. In the lower outer edge of each of the posts of the upper section 2 is formed a transverse groove or kerf 34. When the sections are nested together or when the upper section is lowered into the lower section, the 80 ends of the spring-catches will bear against the outer sides of the posts. When, however, the upper section is raised, the moment it reaches its full extended position or, in other words, the moment the kerfs or grooves 34 85 come opposite the extreme upper bent ends of the hooked portions of the catches, said ends will automatically spring into the kerfs or grooves 34, preventing the entire withdrawal of the upper section and locking it in 90 its raised position. To nest the sections one within the other, it is only necessary to turn the rock-shafts in the manner before described, thus withdrawing the catches, when the upper section will drop by gravity into the 95 lower section, and the two may then be locked together by means of the turn-buttons, as before described.

In Figs. 5 and 6 I have shown a slightly-modified form of spring-catch. When constructed as shown in said figures, the coiled springs are dispensed with and the catch 23^a itself is made of resilient metal and rigidly fastened at its lower end to the post by screws or similar fastenings, as shown. The catches 23^a may be operated from the exterior of the 100 crate by a rock-shaft in the same manner as described with reference to the catches 23, or an opening 35 may be bored in each of the 105 posts partially to one side of the hooked portion of the catch, so that by inserting a hooked 110 rod or wire or a key the catch may be engaged and drawn outward out of engagement 115 with the kerfs or grooves in the posts of the upper section, as before described.

The crate is adapted for shipping poultry, 120 eggs, fruit, and produce of all kinds, and in some cases—as, for example, when the crate is designed for shipping poultry—a bottom or floor 36 may be fitted in the lower end of the 125 upper section 2, and when employed for such purpose doors (not shown) will be provided in the sides of the sections in the usual manner. By providing each section with hinged 130 lids, as 6 and 13, the crate may in practice be used with either section uppermost, or when the bottom 36 is employed one section may be filled with one kind of article and the other section with another kind.

I have shown the crate as comprising but 130 two sections; but it will be obvious that it may be constructed with any desired number of sections. When used for shipping fruit, the crate may be reversed, so that the section

2 will be lowermost or beneath the section 1, and in such case a loose floor or partition may be arranged to rest on the section 2 at the bottom of section 1 to support the weight of the 5 fruit in the latter section and prevent it from bearing upon or crushing the fruit in the section 2.

In Figs. 5 and 6, illustrating the key in position for retracting the spring-catch, I have 10 shown the key inserted from one side of the spring-catch; but it will be manifest that a perforation may be formed in the spring-catch, through which the hooked end of the key may be inserted and then turned to engage the 15 rear or inner side of the catch.

Having described my invention, what I claim is—

1. A shipping-crate, consisting of separable telescoping crate-sections each having a lid at 20 its outer end, concealed spring-catches mounted on the inside portion of one crate-section and automatically springing into engagement with the other crate-section to lock said sections together when extended, means for connecting with and retracting the spring-catches from the exterior of one 25 crate-section to permit the crate-sections to be lifted one from the other or the inner section to move into the outer section, and devices on the exterior of one 30 crate-section constructed to interlock with the other when the sections are moved into one another, substantially as described.

2. A shipping-crate, consisting of two separable telescoping crate-sections each having a lid and the lid of the inner crate-section projecting outward beyond the sides thereof to rest against the inner end of the outer crate-section when the crate is collapsed, concealed 35 spring-catches mounted on the inside portion of one crate-section and automatically springing into engagement with the other crate-section to lock the crate-sections together when extended, means for connecting with and retracting the spring-catches from the exterior 40 of the crate to permit the crate-sections to be lifted one from the other or the inner section to move into the outer section, and locking devices carried by the inner end of the outer 45 crate-section for engaging the said projecting edge of the lid on the inner crate-section to rigidly lock said sections together when collapsed, substantially as described.

3. A shipping-crate, consisting of two separable telescopic crate-sections, the outer one 55 having transverse orifices and on its inner side provided with grooves leading, respectively, to said orifices, spring-catches secured in said grooves and having their engaging ends lying opposite the inner ends of said transverse orifices and constructed to automatically spring 60 into engagement with the inner crate-section

when the crate is extended, means for passing through said orifices from the exterior of the crate and engaging the spring-catches to retract them to permit the crate-sections to be 65 lifted one from the other or the inner section to move into the outer section, and locking devices arranged on the inner end of the outer crate-section and constructed to interlock with the lid of the inner crate-section when the latter is moved into the outer section, substantially as described.

4. A shipping-crate, consisting of inner and outer telescoping crate-sections, the inner section having a lid extended outward from its sides to rest against the inner end of the outer section when the crate is collapsed, concealed 75 catches arranged on the inside portion of the outer section to engage the inner section and lock the crate extended, means for connecting 80 with and retracting the catches from the exterior of the crate to permit the crate-sections to be lifted one from the other or the inner section to move into the outer section, and locking devices arranged on the exterior of one section and constructed to engage the other when the inner section is moved into the outer to rigidly lock said sections together, substantially as described.

5. A shipping-crate, consisting of two separable telescoping sections, the inner one provided at its outer end with a cover projecting laterally beyond the sides of said section to rest upon the edge of the outermost section when the inner section is moved into the outer 95 section, devices mounted on the inner end of the outer section and constructed to interlock with said projecting part of the lid, and spring-catches for locking the sections when extended, substantially as described.

6. In a crate, the combination with two telescoping sections, the innermost of said sections being provided at its outer end with a cover projecting laterally beyond the sides of said section and arranged when the sections 100 are nested together to rest upon the edge of the outermost section, said projecting edge of the cover being provided with an elongated slot, and a turn-button rotatably fixed in the edge of the outermost section and adapted to project through the slot in the said projecting edge of the cover and to be turned at an angle to the slot to rigidly lock the sections in their nested positions, substantially as described.

In testimony whereof I have hereunto set my hand in presence of two subscribing witnesses.

WILLIAM R. AMBROSE.
